UNITED STATES PATENT OFFICE.

ISAAC C. KIGGINS, OF ELIZABETH, NEW JERSEY.

CASE FOR BOOKS.

SPECIFICATION forming part of Letters Patent No. 439,782, dated November 4, 1890.

Application filed May 26, 1890. Serial No. 353,124. (No model.)

To all whom it may concern:

Be it known that I, ISAAC C. KIGGINS, a citizen of the United States, residing at Elizabeth, in the county of Union and State of New Jersey, have invented a new and useful Improvement in Cases for Books; and the following is declared to be a full, clear, and exact description of the same.

My invention relates to cases for spring-back books—such as ledgers and other account-books and blank-books—and particularly to the hubs upon the backs of such books. These cases have heretofore been made up by hand, there being at the back of the book a curved strip of binder's board upon which cut-out pieces of leather or binder's board are glued to make the single or double thickness hubs the leather covering the back being while wet drawn or stretched over the said hubs, and back of binder's board and shaped to conform to the inequalities of the parts, and this hand-work is expensive.

My invention is a new article of manufacture; and it consists in a case for spring-back books wherein the hubs on the back are stamped up by pressure in a strip of binder's board and the leather of the back, and these hubs may be single or double and of any desired width, length, and depth according to the size of the book, and these hollow hubs may be stamped up by a single operation or a succession of operations.

Cases of my improved form are made in standard sizes, and are an article of merchandise adapted to a case to receive the sewed signatures forming the leaves of the book.

In the drawings, Figure 1 is a plan view of the inner face of the case as laid open, and Fig. 2 is a cross-section of the case through one of the hubs.

The case is made with the two sides *a a'* of binder's board, which form the covers of the

book. The leather *b* or other similar material forming the finished face of the case extends over the surface of said sides *a a'* and 45 across between them where the back is to be formed, and the edges of the leather around three edges of the said sides *a a'* are turned over and secured upon the inner face of said sides. A strip of binder's board *c* is secured 50 to the leather equidistant from the opposite edges of the sides *a a'*, and while this strip *c* and the leather *b* are wet and pliable the same are stamped up in heated dies to impart the curved form of the back and simultaneously 55 to press outward in the moist strip and leather the swelled portions or hubs upon the back. These hubs, according to the size of the case, may be single or double and of any desired length, width, or depth, and the parts 60 being stamped in heated dies dries out the moisture and sets the parts so that the proper shape is insured and maintained.

In Fig. 2 the sides *a a'* are shown by dotted lines in their closed position. 65

My improved case is readily and quickly made in a thorough and accurate manner, and the expensive hand-labor heretofore employed in making books in the usual manner is rendered unnecessary. 70

I claim as my invention—

As a new article of manufacture, the curved back-case for spring-back books formed of covered binder's board of nearly uniform thickness throughout and having hollow 75 backwardly-projecting ribs or hubs, substantially as specified.

Signed by me this 16th day of May, A. D. 1890.

ISAAC C. KIGGINS.
